PIANO TOUCH INSTRUCTOR

Loren R. Withers, 2741 Dogwood Road, Durham, N.C.

Filed Aug. 3, 1965, Ser. No. 86,426

Term of patent 7 years

(Cl. D25—1)

FIG. 1

FIG. 2

FIG. 3

FIG. 4

FIG. 5

FIG. 6

FIG. 7

FIGURE 1 is a side elevation of a piano touch instructor showing my new design.

FIGURE 2 is a top view of the touch instructor as shown in FIGURE 1.

FIGURE 3 is a bottom view of the touch instructor of FIGURE 1.

FIGURE 4 is a bottom view of the top plate of the touch instructor as shown in FIGURE 1.

FIGURE 5 is a top view of the bottom plate of the touch instructor as shown in FIGURE 1.

FIGURE 6 is a left-hand elevation view of the touch instructor as shown in FIGURE 1.

FIGURE 7 is a right-hand elevation view of the touch instructor as shown in FIGURE 1.

The broken line showing of a weight seen in FIGS. 1, 2, 6 and 7 is for illustrative purposes only.

I claim:

The ornamental design for a piano touch instructor, substantially as shown and described.
